FURNACE

Thomas G. Coghlan, Elizabeth, and Einar A. Johnsen, deceased, late of Mountain Lakes, N. J., by Sigrid A. Johnsen, executrix, Brooklyn, N. Y.

Original application July 21, 1925, Serial No. 44,957. Divided and this application June 12, 1930. Serial No. 460,615

4 Claims. (Cl. 110—165)

This application is a division of a prior application of applicants, S. N. 44,957, filed July 21, 1925, on which Patent No. 1,898,479 was granted Feb. 21, 1933. The novel features of the invention will 5 be best understood from the following description and the annexed drawings, in which is shown a selected embodiment and in which;

Fig. 1 is a vertical sectional view through a portion of a furnace and associated boiler showing 10 the invention applied thereto;

Fig. 2 is a view on the same plane as Fig. 1, but with parts shown in section, this view being on an enlarged scale and showing certain features of the invention;

Fig. 3 is a fragmentary section on the line 3—3 of Fig. 4 illustrating one of the pipe control valves; and Fig. 4 is a plan view of the valve shown in Fig. 3.

Referring now to Fig. 1, there is shown therein 20 a furnace having a lower combustion chamber 1 and an upper combustion chamber 2 connected by a restricted throat 3. In the lower part of the chamber 1 is a fuel burning means exemplified by a chain grate 4, to which fuel is supplied from 25 a hopper 5.

Gases from the upper chamber 2 pass upwardly through a pass 6 downwardly through a pass 7 and again upwardly through a pass 8 to an outlet 9. Extending across the three passes are 30 water tubes 10 connected at opposite ends to headers and inclined slightly to the horizontal in a manner well known in the art. Above the passes 6 and 7 is disposed a superheater 11. After reaching the outlet 9, the gases are conducted 35 through an air heater 12, and the air from this heater may be supplied to the furnace in a manner more fully described in the said copending application.

The dust contained in the gases as they pass 40 over the boiler tubes and through the air heater may contain a considerable amount of unburned fuel, and it is desirable to return such fuel to the fuel bed. In the illustrated embodiment this is accomplished by providing a hopper 13 beneath 45 the lower edge of the baffle which separates the passes 7 and 8 and another hopper 14 in the air heater. These hoppers, particularly the hopper 13, are so placed as to collect dust which may be precipitated by the gas stream when it changes 50 its direction as beneath the lower edge of the baffle.

Leading from the bottoms of the hoppers 13 and 14 are pipes 15 and 16 which are joined together at the junction 17, and the dust flowing 55 through these pipes is conducted by a third pipe

18 through an arch 19 over the lower part of the grate 4, so that it will be deposited upon the fuel bed on this grate. The fuel on the rear part of the grate is burned under the arch 20 to a great extent and, preferably, the supply of air to the 60 lower portion of the grate is such as to cause an excess of oxygen, whereby the dust or more accurately the fuel in the dust may be thoroughly burned.

Referring now more particularly to Fig. 2, we 65 have shown the pipe 18 as being reduced at 21 to form a throat or portion of restricted cross-sectional area to increase the velocity of the stream of dust flowing therethrough. On the side of the throat away from the furnace chamber 70 is disposed the discharge opening 22 from the pipe 17, and between this discharge opening and the throat is disposed a nozzle 23 on a pipe 24 which is connected to a suitable source of hot air. Conveniently this air may be supplied from 75 the air heater 12, the details of the connection thereto being omitted, as that is only one example of a suitable source of hot air. The hot air passing through the pipe 24 is normally under 80 pressure, as is usually the case with hot air being supplied to a combustion chamber, and its velocity is increased as it passes through the nozzle 23, and this velocity is still further increased at the throat 21. In other words, the nozzle 23 forms an aspirating tube to draw the stream of 85 dust from the discharge opening 22 and to increase its velocity and, consequently, its pressure. The pressure by this arrangement is increased 90 enough to overcome the pressure in the chamber 1.

The pipes 15, 16 and 24 are preferably provided with suitable slide valves 25, 26 and 27 respectively, by means of which the quantity of the material flowing therethrough may be varied, as found desirable. Similar valves may be used in 95 the three pipes, the valve 25 in the pipe 15 being shown in detail in Figs. 3 and 4.

What is claimed is:—

1. A steam generator having a combustion chamber, a relatively long combustion arch extending forwardly over the rear part of said combustion chamber, a traveling fuel grate in said combustion chamber extending below said arch, a steam boiler arranged above said combustion chamber, a dust settling chamber below a rear portion of said steam boiler in a position to receive dust separating out from the products of combustion flowing through said boiler from said combustion chamber, and means for returning 100 collected dust from said settling chamber in sus- 110

50 suspension in an air stream to the space in said combustion chamber between said arch and the rear portion of said grate.

51 2. A steam generator having lower and upper combustion chambers, front and rear combustion arches extending over said lower chamber and arranged to form a restricted throat between said lower and upper chambers, a traveling fuel grate in said lower chamber having its fuel feed end 52 extending below said front arch and its ash discharge end extending below said rear arch, a steam boiler arranged above said upper chamber, a dust settling chamber below a rear portion of said steam boiler in a position to receive dust 53 separating out from the products of combustion flowing through said boiler from said upper combustion chamber, and means for returning collected dust from said settling chamber in suspension in an air stream to the space in said 54 lower chamber between said rear arch and the rear portion of said grate.

55 3. A steam generator having lower and upper combustion chambers, front and rear combustion arches extending over said lower chamber and arranged to form a restricted throat between said lower and upper chambers, a progressive feed fuel grate in said lower chamber having its fuel feed end extending below said front arch and its ash discharge end extending below said rear arch, a means for passing air for combustion upwardly through the fuel bed on said grate with an excess of air above the rear portion of said grate, a steam boiler arranged above said upper chamber, a dust hopper below a rear portion of said 60 steam boiler in a position to receive dust separating from the products of combustion flowing through said boiler from said upper combustion chamber, and means for returning collected dust under pressure from said hopper to the space in said lower chamber between said rear arch and

65 the rear portion of said grate comprising a dust conduit connected to said hopper and opening to said lower chamber through said rear arch, and a fluid ejector arranged to discharge into said conduit towards said lower chamber to convey the dust therein under an increased pressure into said lower chamber.

70 4. A steam generator having lower and upper combustion chambers, a relatively short rear combustion arch extending over said lower chamber and arranged to form a restricted throat between said lower and upper chambers, a chain grate in said lower chamber having its feed end extending below said front arch and its ash discharge end extending below said rear arch, means for passing air for combustion upwardly through the fuel bed on said grate with an excess of air above the rear portion of said grate, a bank of boiler tubes arranged above said upper chamber, a dust hopper below a rear portion of said tube bank in a position to receive dust separating from the products of combustion flowing through said boiler from said upper combustion chamber, means for returning the collected dust under pressure from said hopper to the space in said lower chamber between said rear arch and the rear portion of said grate comprising a dust conduit connected to said hopper and opening to said lower chamber through said rear arch, an air ejector arranged to discharge into said conduit in the direction of flow, and a flow constriction in said conduit arranged to increase the pressure of the air and dust mixture before said mixture may enter said lower chamber.
